Meyers, Cushman & Reed

UNITED STATES PATENT OFFICE.

ANTHONY SCHNEIDER, OF WHIPPANY, NEW JERSEY.

CIGAR-BOX.

1,268,164.

Specification of Letters Patent. Patented June 4, 1918.

Application filed May 29, 1916. Serial No. 100,543.

To all whom it may concern:

Be it known that I, ANTHONY SCHNEIDER, a citizen of the United States, residing at Whippany, in the county of Morris and 5 State of New Jersey, has invented certain new and useful Improvements in Cigar-Boxes, of which the following is a specification.

This invention relates to certain novel 10 and useful improvements in boxes and has particular application to a composite box of the humidor type adapted especially for the packing, shipping and storing of cigars, and serving as an original package.

15 In the present instance I propose to provide a composite cigar box which embraces among other features an outer case or shell, preferably of metal, within which is located an inner section or shell, preferably of a 20 fragrant wood, such as cedar or a substitute thereof. By making the outer case of metal, such as tin or the like, I insure the protection of the contents of the package against atmospheric influence and at the 25 same time give the requisite and necessary strength to such package to protect the contents from damage and injury which might result in the rough usage which is liable to occur in the transportation, storage and 30 handling of the package. By employing an inner casing of wood, such as cedar, or substitutes, I avoid the contact of the cigars with the metal thereby obviating the imparting of a metallic taste to the cigars 35 which will ruin their flavor and aroma. Furthermore, the use of such a fragrant wood as cedar, or substitutes, as is well known, will impart to the cigars a pleasing aroma.

40 Furthermore, it is my purpose to provide as an original package a composite cigar box which will itself serve the purpose of a humidor for preserving and storing the cigars inasmuch as the exterior metal case 45 will serve such purpose, and in addition possess the advantage that it constitutes a part of the original container in which the goods are initially packed, shipped and sold.

I also propose in the present instance to 50 provide a composite box of this character wherein a wooden lining or shell, preferably of cedar, is provided with a top or cover also of wood, such as cedar, which is arranged in such manner, and is so constructed 55 that when closed it will lie within the confines of and substantially flush with the top

edge portions of the front and end walls of the wooden lining or shell. The front, rear and end walls extend above the adjacent side and end walls of the metal case, so 60 that when the cover of such metallic case is closed, the depending flanges of the metallic cover will overlie the projecting portions of the side and end walls of the wooden shell or lining, while the top wall of the metallic 65 cover will bear against the wooden lid or cover.

By this arrangement I insure that the contents of the box will be adequately preserved from atmospheric conditions, such as 70 moisture and the like, while at the same time no part of the metal of the box will be in contact with or adjacent the cigars.

Furthermore, I provide means through the agency of which both the tin cover of the 75 case and the wooden lid or cover of the box may be easily, readily and simultaneously opened, this arrangement being particularly useful in the initial opening of the box.

I also aim to provide a composite cigar 80 box which will embody the desired features of simplicity, efficiency and convenience, and which may be manufactured and marketed at a relatively low cost.

With the above recited objects and others 85 of a similar nature in view, my invention consists in the construction, combination and arrangement of parts set forth in and falling within the scope of the appended claims.

In the accompanying drawings, 90

Figure 1 is a perspective view of a cigar box embodying my invention, the cover of the outer case or shell being shown as fully opened, while the cover of the inner lining or shell is shown as partially opened.

Fig. 2 is a transverse vertical sectional view taken through a closed box embodying my invention.

In the present instance I have shown and described the inner shell or lining of my 100 improved box as composed of separate strips or pieces of thin wood, preferably cedar, loosely assembled within the case, as this is conducive to economy in the cost of production of the composite box, but I wish it 105 to be understood that if desired, this inner lining or shell may have the walls thereof united or joined together in the ordinary manner.

Referring now to the accompanying drawings in detail, the letter A indicates the exterior case or shell of my improved box,

while B designates the cover thereof. The body of the box A, as well as the cover B, is preferably made from relatively thin sheet metal, such as tin or the like. The body 5 portion of this metallic case is provided with an exterior bead 1; this bead constituting a stop by engaging with the flanges 2 of the cover B when the box is closed. The upper edge of the front wall of the box body A 10 is formed with an integral projection or prominence 3, which is adapted to engage with the front flange of the cover to pinch the tab hereinafter referred to for a purpose which will appear and to lock the cover in 15 its closed position, as will be readily understood. Within the body A of the metallic case I arrange a shell or lining, preferably of cedar or other aromatic wood, which is indicated as an entirety by the letter C. 20 This lining comprises a bottom wall 4, end walls 5—5, front wall 6, and a rear wall 7. The lid wall or cover of the box is shown at 8 and is hinged as at 9 to the top edge of the rear wall. The two end walls 5—5, 25 the front wall 6 and the rear wall 7 of the lining or shell C all have their top marginal edge portions projecting a considerable distance above the adjacent walls or sides of the metallic box body A, as is clearly shown 30 in Fig. 1. Furthermore, the two end walls 5—5 and the front wall 6 of this cedar shell C are of the same height, and in turn are of relatively greater height than the rear wall 7, as will be understood by reference to Fig. 35 1, this difference in height being substantially equal to the thickness of the wooden cover 8, so that when this cover 8 is closed down, the outer face of the same will lie substantially flush with the top edges of the 40 side walls 5—5 and the front wall 6, thereby insuring a tight lining or shell for protecting the cigars. It will also be noted that by reason of the fact that the vertical walls of the inner shell or lining C are higher 45 than the vertical walls of the metallic or outer shell A, when the cover B of this metallic shell is closed it will not contact with or be exposed directly to the contents of the box, and therefore the liability of a metallic flavor being imparted to the cigars is 50 avoided, while at the same time the top section of this wooden lining or shell C will be nested or fitted within the cover, this top section of the wooden lining or shell of 55 course comprising the cover 8 and the projecting top edges of the front wall 6, the end walls 5 and the rear wall 7. The result will be a tight, compact, atmosphere-proof package in which the cigars will be entirely 60 enveloped by the cedar lining and protected from the metallic shell and at the same time such metallic shell will completely envelop this cedar lining and perform the protective functions for which it is designed as above 65 mentioned. As stated, the inner lining or

shell may consist of separate strips or pieces loosely assembled within the metal case.

As is well known, cigar boxes have the revenue stamps pasted thereon in such manner that the stamps overlie certain parts of 70 the top and sides of the box, thereby sealing the latter, these stamps being ruptured or broken when the cover is opened. In the present instance, the stamps would of course be pasted upon the metallic case or cover, 75 and to provide access to the contents I fasten, as at 9' to the wooden cover 8, preferably near the front edge thereof and at the center line of the cover, a suitable finger tab 10, which may be of any preferred material, 80 such as a piece of ribbon fabric, leather, or the like. When the wooden cover is closed, as shown in Fig. 2, this tab is adapted to extend outward and to overlie the catch or latching projection 3 on the metallic case, 85 the front section of the flange 2 of the metallic cover pinching the tab inward against the front wall of the body portion of the metallic case to securely hold the cover 8 within the confines of the front and end 90 walls of the inner shell and at the same time such pinching of the tab 10 serves to hold the cover of the outer case B positively closed over the inner shell, as is shown in Fig. 2. In opening the box, it is only necessary to grasp this finger tab and pull upward on the same, when both the metallic cover B and the wooden cover 8 will be lifted. Of course if the metallic case is covered exteriorly with labels and the like, 100 which overlap the meeting edges of the cover and the box it may be convenient to first cut or slice the labels with a sharp knife, as will be readily understood.

From the above description taken in connection with the accompanying drawings, the construction and operation of my invention will be readily understood and appreciated. It will be noted that I have provided a composite box which constitutes the 105 original container for the cigars when they are sent from the factory, and which will form a humidor for protecting the cigars when they are in the hands of the consumer for his use. Furthermore, it will be seen that both of the covers of the box may be lifted simultaneously, thus avoiding the necessity of handling the two covers separately with the liability of having the fingers caught or jammed between the two covers. 115

It will further be noted that by arranging the wooden lid or cover for the cedar lining or shell as herein described, I insure that the cigars may be packed and pressed in this lining like in any regularly constructed and packed cedar cigar box.

In actual practice, the exterior faces of the metallic case are printed, lithographed or otherwise marked in imitation of the grain of wood, in the present instance cedar,

so that the box in outward appearance will resemble a box made from cedar wood.

While I have herein shown and described one particular embodiment of my invention, 5 I wish it to be understood that I do not confine myself to all the precise details of construction herein set forth by way of illustration, as modification and variation may be made without departing from the spirit 10 of the invention or exceeding the scope of the appended claims.

What I claim is:

1. A composite cigar box comprising an outer metallic case and an inner wooden shell, the vertical walls of said wooden shell being higher than the adjacent vertical walls of the metallic case, said wooden shell having a cover hinged to its rear wall and adapted to lie substantially flush with the 15 top edges of the remaining vertical walls of such shell when the cover is closed, said metallic case including a hinged cover having depending flanges adapted to overlie the portions of the walls of the shell which project 20 above the adjacent walls of the metallic case, and means attached to the cover of the inner shell for simultaneously lifting or opening both covers and for holding both 25 covers closed.
2. A cigar box comprising an outer case and an inner shell, a hinged cover for the outer case, a hinged cover for the inner shell, and flexible means attached to the cover of the shell and accessible from the exterior of 30 the case when the latter is closed, for simultaneously lifting or opening both covers, and for holding the cover of the outer case closed over the inner shell with its cover held closed.
3. A composite cigar box comprising an outer metallic case and an inner cedar shell, the vertical walls of said cedar shell being higher than the adjacent vertical walls of the metallic case, the rear wall of said shell 35 being of less height than the front and end 40

walls of the shell, a cover hinged to the top edge of said rear wall and adapted when closed to lie substantially flush with the top edges of the front and end walls of the shell, a hinged cover for the metallic case, and 50 flexible means connected with the cover of the cedar shell and accessible from the exterior of the case for simultaneously lifting both the covers, and a prominence on the front wall of the outer case with which said 55 flexible means combines to hold both covers positively closed.

4. A composite cigar box comprising an outer metal case having a flanged cover hinged thereto, and a removable lining for 60 the case comprising a bottom, lid and side members, the upper edges of the side members extending above the marginal edges of the metal case, the said cover flange being of sufficient depth to embrace, when closed, 65 the said extending edges of the side members and overlie the marginal edges of the case, and a flexible tab secured at one end to the said lid and having its other end externally accessible when the case cover is closed to 70 permit concurrent lifting of both the cover and the lid.

5. A composite cigar box comprising an outer case having a hinged cover, an inner shell also having a cover hinged to permit 75 opening of both covers concurrently, said shell cover, in closed position, extending below the top plane of the front vertical wall of the shell and having its front edge spaced from the case walls by said shell wall, and 80 means carried by the shell cover and externally accessible when the case is closed for permitting concurrent lifting of both covers.

In testimony whereof I affix my signature in the presence of two witnesses.

ANTHONY SCHNEIDER.
